SHOE SEWING MACHINE

Ralph E. Pearsall, Gloucester, Mass., assignor to United Shoe Machinery Corporation, Flemington, N. J., a corporation of New Jersey

Application November 7, 1952, Serial No. 319,255

5 Claims. (Cl. 112—47)

This invention relates to improvements in machines for sewing together the parts of a slip-lasted shoe while the edges of its parts are being brought into register, the upper of the shoe being given a rough shoe formation during the sewing operation.

The usual practice in the manufacture of a slip-lasted shoe includes the provision of a shoe upper cut with an accurate pattern designed to form a shoe when its edges are brought into register with those of an unchanneled blank of relatively thin flexible woven sheet material shaped to correspond with the sole of the shoe. In bringing the edges of the parts into register, some force is required and skill is essential to overcome the resistance offered by the material operated upon, against deforming it from its natural flattened condition. The greatest force and essential skill required in sewing together the shoe parts is exercised while operating along the abrupt curvature at the toe portion of the shoe. In sewing the toe portion of a shoe it is necessary to swing the shoe rapidly so that the stitches will be inserted substantially at right angles to the shoe parts at the point of sewing operation. To hold the parts in sewing position they are gripped by a clamp in the usual form of a work support and presser foot.

The most desirable type of sewing machine for use in the manufacture of ordinary slip-lasted shoes is a commercially available straight needle machine arranged with a work feeding clamp and a nonfeeding work clamp acting alternately to maintain a continuous grip on the edges of the shoe parts so that an operator's full attention may be exercised in bringing the edges into proper registry while the clamps hold the parts thereafter during insertion of the stitches.

The usual form of machine, having work feeding and nonfeeding work clamps is arranged with the nonfeeding clamp located along the direction of feed at the left of the sewing point while maintaining clear visibility at the sewing point. With such location the feeding clamp pushes the material shoe parts operated upon through the nonfeeding clamp tending to crumple them and the nonfeeding clamp flattens the crumpled parts in a manner which distorts them permanently. When operating upon the edges of slip-lasted shoe parts with the usual machine of this type, particularly where relatively sharp serrated work engaging surfaces are provided on the clamps, a serious difficulty arises from the tendency of the serrations to impale or tear the sheet material comprising the sole in a manner to impair proper feeding movement or to damage the material. Usually, shoes constructed on machines of this type require applications of heat, wetting of the distorted parts and hand repair operations before acceptable results are obtained.

The object of the present invention is to improve the manner of operation and the construction of slip-lasted shoe sewing machines, in which the difficulties of feeding and clamping the edges of the two parts noted are avoided while retaining visibility of the parts at the point of sewing operations, and in which the edges of the parts are easily brought into proper register in advance of the sewing point with less skill and attention on the part of the machine operator than heretofore needed. A further object is to improve the quality and volume of work performed by a machine of the type referred to, by providing an arrangement of clamps in the machine, which enable a more accurate register than heretofore considered possible along the edges of the parts in a slip-lasted shoe

2

being sewn together without distortion of the parts or other damage to the resulting shoe. In the attainment of these and other objects a sewing machine for operating upon slip-lasted shoes is provided having the usual stitch forming devices including a needle and a work feeding clamp acting to grip the material of a shoe about the point of needle operation in which a nonfeeding work clamp acting while the feeding clamp is being back fed, has a work engaging surface limited to a small area located with respect to the direction of feed in advance of the work feeding clamp only so that instead of pushing the edges of the parts operated upon through the nonfeeding clamp, they are pulled through by the feeding clamp. Preferably, the nonfeeding clamp comprises a stationary work support plate having an aperture through which a feed dog projects and a presser foot having a work engaging surface limited to an area located with respect to the direction of work feed opposite a stationary portion of the plate in advance of the perforation therein, the nonfeeding presser foot being formed with an arm provided with a recess through which the feeding presser foot moves both toward and from the work and in the direction of work feed. By so doing it is possible to utilize a machine already commercially available, in which there is arranged a reciprocating needle bar to which the needle is secured, a work feeding presser foot bar and a nonfeeding presser foot bar, all mounted for movement in substantially parallel relationship, forming a row one behind another, along the direction of work feed in the order stated. Thus, a machine is provided complying with all requirements for visibility in advance of the point of needle operation so that the work operated upon may be guided with the greatest possible facility.

These and other features of the invention, as hereinabove described and claimed, will be pointed out in connection with the following detailed specification, taken in connection with the accompanying drawings, in which:

Fig. 1 is a view in front elevation of portions of a slip-lasted shoe sewing machine embodying the features of the present invention and illustrating parts of a shoe, broken away and shown in section, while being presented to the machine;

Fig. 2 is a view in left side elevation of the machine parts and shoe illustrated in Fig. 1;

Fig. 3 is a sectional plan view taken along the line III—III of Fig. 2; and

Fig. 4 is a detailed view of the work support and feed dog of the machine indicating the gripping areas of the work clamps.

The illustrated machine is intended for sewing while unsupported by a last the margins of the parts in a slip-lasted shoe with the edges of the parts registering. During sewing the parts are deflected from their normal flattened condition and are shaped progressively into the configuration of a shoe. The parts of a slip-lasted shoe of conventional construction include an upper 6 cut with an accurate pattern and an unchanneled blank 8 of relatively thin flexible woven material shaped to correspond with the sole of the shoe. Both shoe parts ordinarily are furnished in a substantially flattened condition and during the sewing operation, the operator is required to deflect their edges progressively while bringing the edges into register in advance of the sewing point. Where hard toe shoes are being manufactured, the toe portion of an upper may be preshaped and provided with a reinforcement 10 of stiffening material which is later activated. Even when preshaped, however, the upper still requires substantial deflection progressively in advance of the sewing point in the machine. Considerable skill is required in deflecting the parts and bringing their edges into accurate register especially about the toe and inside shank of the shoe, a substantial tension being imparted to the sole blank while it is being sewn to the upper 6, which is of substantially larger area than the sole blank. Also, a right angle flange is formed in the sole blank margin during the sewing operations by work gripping clamps in the machine, the sole blank being relatively more flexible than the upper. As a result of the right angle flange in the sole blank there is a tendency for it to cling to the upper members of the work clamps, par-

ticularly when they are arranged in side-by-side relation and when sharp serrations are cut in the work engaging areas of the clamps, retarding the work feed or damaging the woven structure of the sock lining. If the shoe is being sewn on the prior machine, in which feeding and nonfeeding clamps are provided acting in side-by-side relation an excessively wide flange will be formed in the sole blank and distortion occurs in the finished shoe. To correct the distortion additional hand operations are required on the shoe before completion.

To avoid the tendency for improper feed of the shoe parts and to reduce the danger of damage or distortion while sewing, the work clamps of the illustrated machine are constructed and arranged in a particularly advantageous manner both for easy visibility and reliable unimpeded feed of the work. Accordingly, the machine is provided with a work feeding clamp, the grip of which on the material operated upon is exerted on an area located in surrounding relation to the sewing point and with a nonfeeding clamp arranged to act while the feeding clamp is being backfed with a work engaging surface limited with respect to the direction of work feed to a confined area located in advance only of the area engaged by the feeding clamp. In other respects the illustrated machine is generally similar to that of a commercially available lockstitch sewing machine.

Referring more particularly to the drawings, the machine has a stationary frame, two separate portions of which are shown, including a work support 12 projecting upwardly from a base portion and an overhanging arm 14 connected integrally thereto. Mounted for reciprocation in the arm 14 are a needle bar 16, a work feeding presser foot bar 18 and a nonfeeding presser foot bar 20. The needle bar 16 has secured to it an eye-pointed needle 22. The feeding presser foot bar 18 has clamped to it a work feeding presser foot 24 formed along its work engaging surface with sharp serrations 26. Clamped to the lower end of the nonfeeding presser foot bar is a nonfeeding foot 28 also serrated along its work engaging surface. The feeding presser foot bar 18 and the needle bar 16 are guided for vertical movement in a feed carriage 30 movable in the arm 14 in the direction of work feed while the nonfeeding bar 20 is slidably mounted for vertical reciprocation in fixed vertical bearings in the arm. This is the usual arrangement of the needle and presser foot bars in the type of machine indicated, the respective bars being arranged in substantially parallel relationship, one behind another with the needle bar in front, the feeding bar 18 just behind the needle bar and the nonfeeding bar at the rearmost location. Such arrangement is conducive to compact design and ready visibility from the front of the machine for convenient manipulation of the work by an operator.

The usual arrangement of the nonfeeding foot is with its work engaging surface acting with respect to the direction of work feed, indicated by the arrow 32 (Fig. 2) directly behind and at the left side of the gripping area of the feeding foot. Cooperating with the presser feet of the prior machine to grip the material operated upon are a feed dog similar to that shown at 34 and a work support plate as shown at 36, the nonfeeding foot gripping the work against the left side of the plate and at the left side of the needle where the main bulk of the shoe parts operated upon are positioned. The feed dog 34 moves horizontally in unison with and vertically in a direction opposite to the vertical movement of the feeding presser foot. The nonfeeding foot ordinarily engages the plate 36 at the left side of a slot through which the feed dog projects. The feeding presser foot 24 is frequently formed with an opening in line with the path of the needle so as to grip the material operated upon closely in completely surrounding relation to the needle about its point of operation, the feed dog 34 having a similar opening aligned therewith.

With the usual arrangement of feeding and nonfeeding work clamps composed respectively of the work feeding presser foot and the feed dog in the first instance and of the nonfeeding presser foot and the work support plate in the second instance, it is apparent that the feeding presser foot will engage the work somewhat in advance and at one side of the nonfeeding foot. On account of the tension in the sole blank 8 and the angular flange formation along its margin, difficulty has been encountered during the back feeding movement of the feeding foot by engagement with the sole blank before the

margin of the blank is effectively flanged and brought into contact with the margin of the upper 6. Furthermore, with the feeding and nonfeeding feet in the usual side-by-side relation, a narrow flange is formed in the sole blank by the feeding foot but as the nonfeeding foot acts a much wider flange is formed, deflecting the parts somewhat from their original relation and crumpling them in advance of the nonfeeding foot. One reason for this difficulty is that under its tension the sole blank resists conformity with the margin of the upper, tending to draw away from it particularly about the toe portion of a shoe, as indicated by the angle 38 in Fig. 2. Also, if the feeding presser foot engages the sole blank during its back feeding movement the extreme edge of the blank may be stretched or the shoe may be moved against the direction of work feed. If sufficient stretching of the sole blank occurs, crumpling takes place at the left of the needle and an improper shape is imparted to the shoe or the blank is damaged by tearing.

The nonfeeding presser foot 28 in the machine of the present invention has its shank so formed and the serrations 26 along its work engaging surface so cut that its work engaging surface acts on the work in a limited area located in advance only of the work feeding foot 24 rather than behind or in side-by-side relation to the feeding foot. As a result, the nonfeeding foot 28 compresses the flange of the sole blank against the upper at the edges only of the parts and closes the angle 38 without influencing in any way the feeding movement or deforming the configuration of the shoe parts after the parts are fed. To enable the nonfeeding foot to be secured to the presser bar 20 the nonfeeding foot is formed with an arm bent around the feeding foot 24 at the side of the needle opposite the main bulk of a shoe being sewn, providing a recess 40 through which the feeding foot 24 and the needle move. The nonfeeding clamp includes the foot 28 and a portion of the work support plate 36 in advance only of the slot, indicated at 41 in the plate. Thus, the feeding clamp composed of the foot 24 and the feed dog 34 are fully protected against undesired contact with the work during their back feeding movements, the feed dog 34 being withdrawn from engagement with the under side of the work through the slot 41 and the nonfeeding foot 28 holding the flange of the sole blank 8 positively out of the path of the serrations 26 along the work engaging surface of the foot 24.

Reference to Fig. 4 will indicate more exactly the relationship of the gripping areas acted upon by the work feeding and nonfeeding work clamps. The work feeding clamp grips the shoe parts along the area, indicated by a dotted rectangle 42, surrounding the point of needle operation and the nonfeeding clamp grips the shoe parts along the area indicated by a dotted rectangle 44 in close proximity to the area 42 in advance only of the sewing point. The desirability of such arrangement is accentuated where relatively short curvatures are encountered around the toe portions and shanks of shoes, inasmuch as the gripping areas 42 and 44 are brought close together after back feeding the feeding clamp, so that the initial gripping force of the feeding clamp is exerted on the curved surfaces of the shoe parts as close as possible to the gripping area of the nonfeeding clamp. Through the close arrangement of the presser feet the angular movements of the shoe parts as they are presented to the machine are disturbed in the smallest possible degree. Also, the location of the nonfeeding foot in advance of the feeding foot and in line with the feeding foot in the direction of feed rather than in side-by-side relation therewith prevents distortion, crumpling or other damage to the shoe.

In order to assist the register of the shoe parts during the sewing operation, the edges of both are brought against an adjustable gage 46 of the usual construction. The gage 46 is adjustable towards and from the sewing point through manipulation of a clamp screw 48 acting on the edge gage and the forward work engaging surface of the gage is formed with a suitably convex face 50. With the use of a nonfeeding clamp acting on a limited area in advance only of the sewing point, the face 50 of the edge gage is located along the line of the seam with its point of contact against the work directly opposite the sewing point of the needle or between the sewing point and the clamping area 44.

To prevent engagement of the nonfeeding presser foot 28 with the edge gage 46, the bend in the arm of the

nonfeeding foot forming the recess 40 is located above the upper surface of the edge gage and the nonfeeding foot has a vertical portion 52 extending upwardly from its gripping area 44 on the work support plate 36 to a position above the level of the edge gage. The vertical portion of the presser foot 28, therefore, terminates at its gripping area on the work within an angle formed by the face 50 of the edge gage and the work engaging surface of the plate 36 in the line of the seam with the needle and feeding foot to form an enclosure for the registering edges of the shoe upper 6 and the sole blank 8 and thus prevents displacement of the shoe part edges at any time during sewing.

The nature and scope of the invention having been indicated and a particular embodiment having been described, what is claimed is:

1. A machine for sewing while unsupported by a last the margin of a shoe upper and an unchanneled blank of relatively thin flexible material shaped to correspond with the sole of a shoe, said machine having a needle and other stitch forming devices, and a work feeding clamp acting to grip the material operated upon about the point of needle operation, in combination with a nonfeeding work clamp acting while the feeding clamp is being backfed and having work engaging surfaces limited to a gripping area located with respect to the direction of feed in advance only of the work feeding clamp.

2. A machine for sewing while unsupported by a last the margin of a shoe upper and an unchanneled blank of relatively thin flexible material shaped to correspond with the sole of a shoe, said machine having a needle and other stitch forming devices, and a work feeding clamp comprising a feed dog and a presser foot acting to grip the material operated upon about the point of needle operation and having work engaging surfaces defining an area surrounding the point of needle operation, in combination with a nonfeeding work clamp acting to grip the material operated upon while the feeding clamp is being backfed and comprising a stationary work support plate through which the feed dog projects, and a presser foot having a work engaging surface limited to an area located with respect to the direction of work feed opposite a portion of the plate in advance only of the point of needle operation and being formed with an arm providing a recess through which the feeding presser foot moves and a nonfeeding presser foot bar to which the nonfeeding presser foot is secured, mounted for reciprocation toward and from the work with respect to the direction of work feed beyond the sewing point.

3. A machine for sewing while unsupported by a last the margin of a shoe upper and an unchanneled blank of relatively thin flexible material shaped to correspond with the sole of a shoe, said machine having a needle and other stitch forming devices, and a work feeding clamp, in combination with a nonfeeding work clamp acting to grip the material operated on while the feeding clamp is being backfed and being located to operate on the work along the line of the seam inserted by the needle only in advance of the work feeding clamp, said work feeding clamp comprising a feed dog located at the side of the work opposite that from which the needle penetrates

the work and a work clamping presser foot movable in the direction of work feed, the nonfeeding clamp comprising a stationary work support plate and a presser foot engaging the work opposite the stationary plate and being formed with an arm provided with a recess through which the feeding presser foot moves, a nonfeeding presser foot bar to which the nonfeeding presser foot is secured, a reciprocating needle bar to which the needle is secured and a feeding presser foot bar to which the work feeding presser foot is secured, said needle, work feeding presser and nonfeeding presser foot bars all being mounted for reciprocation in substantially parallel relationship one behind another along the direction of work feed in the order last stated.

4. A machine for sewing while unsupported by a last the margin of a shoe upper and an unchanneled blank of relatively thin flexible material shaped to correspond with the sole of a shoe, said machine having a needle and other stitch forming devices, and a work feeding clamp acting to grip the material operated upon in surrounding relation to the point of needle operation, in combination with a nonfeeding work clamp acting while the feeding clamp is being backfed and having work engaging surfaces limited to a gripping area located with respect to the direction of feed in advance only of the work feeding clamp, said feeding and nonfeeding clamps including a feeding presser foot and a nonfeeding presser foot formed with an arm bent around the feeding foot at the side of the needle opposite the main bulk of the shoe parts being sewn.

5. A machine for sewing while unsupported by a last the margin of a shoe upper and an unchanneled blank of relatively thin flexible material shaped to correspond with the sole of a shoe, said machine having a work feeding needle and other stitch forming devices, a work feeding clamp acting to grip the material operated upon about the point of needle operation, and an edge gage along which the upper and sole blank are guided into the point of needle operation, in combination with a nonfeeding work clamp acting while the feeding clamp is being backfed and having work engaging surfaces limited to a gripping area located with respect to the direction of feed in advance only of the work feeding clamp, said work clamps including feeding and nonfeeding presser feet, a feed dog and a work support plate through which the feed dog moves, the nonfeeding presser foot being formed with an arm bent around the feeding foot at the side of the needle opposite to the main bulk of the shoe parts being sewn and having a vertical portion extending upwardly from its gripping area and terminating at a position above the level of the edge gage.
